WATER COOLED STOKER

William V. Sauter, Philadelphia, and Joseph S. Bennett, Merion, Pa., assignors to American Engineering Company, Philadelphia, Pa., a corporation of Pennsylvania

Application November 23, 1938, Serial No. 241,898

13 Claims. (Cl. 122—4)

This invention relates to stoker furnaces, and more particularly to stokers of the fluid cooled type.

One object of the present invention is to provide a simplified and generally improved stoker of the fluid cooled type which insures continuity of service under all conditions of operation.

Another object is to provide in a stoker of the stated character improved tuyère constructions having extended surfaces disposed in intimate contact with fluid conducting tubes and the incoming draft air, whereby they are maintained relatively cool during operating periods of the furnace.

A further object is to provide tuyère members of resilient construction to enable the ready assembly thereof on the tubes of the fluid cooled section of the stoker, and to insure proper contact between said members and the tubes.

Other and further objects will become apparent as the description of the invention progresses.

Of the drawings:

Fig. 1 is a longitudinal sectional view taken through one of the retorts of an inclined grate underfeed stoker.

Fig. 2 is a transverse sectional view taken through one of the tuyère chambers of the stoker shown in Fig. 1, showing the construction of the tuyère members forming the preferred embodiment of the present invention.

Fig. 3 is an enlarged fragmentary side view, showing the construction of the side tuyère members of the tuyère unit shown in Fig. 2.

Fig. 4 is a longitudinal sectional view taken through one of the tuyère chambers of the stoker shown in Fig. 1.

Fig. 5 is a view taken substantially along line 5—5 of Fig. 4.

Fig. 6 is a sectional view taken substantially along line 6—6 of Fig. 4.

Fig. 7 is a transverse sectional view illustrating another embodiment of the present invention.

Fig. 8 is a sectional view taken substantially along line 8—8 of Fig. 7.

Fig. 9 is a perspective view of one of the intermediate tuyère members shown in Figs. 7 and 8.

Fig. 10 is a transverse sectional view of a further embodiment of the present invention.

Fig. 11 is a view partly in section, taken along line 11—11 of Fig. 10, and

Fig. 12 is a perspective view of one of the tuyère members shown in Figs. 10 and 11.

Referring to the drawings, the numeral 1 designates generally a stoker of the inclined grate, underfeed type, having alternately disposed re-

torts 2 and tuyère rows 3. The bottom of each retort has provided therein a series of alternately disposed pushers 4 and dead plates 5. Fuel is supplied to the stoker from hoppers 6 disposed exteriorly of the front wall 7 of the furnace. The fuel gravitating in hoppers 6 enters cylinders 8 from which it is fed to the retorts 2 by means of rams 9 operated by any suitable power mechanism 10. The fuel is underfed along the stoker by the pushers 4, the consumed fuel being fed into an ash pocket A disposed at the end of the stoker. The pushers 4 are also actuated by the power mechanism 10 through the link and lever mechanism indicated generally at 11.

Each retort 2 is defined at the sides thereof by inclined, longitudinally extending side plates 12 and 13, which also define the sides of the tuyère chambers 14 disposed between adjacent retorts 2. Side plates 12 and 13 have supported thereon series of tuyère supports 15 and 16 respectively. Tuyère supports 15 and 16 are secured to the inwardly extending flanges 17 and 18 respectively, of side plates 12 and 13 by any suitable means, such as by bolts 19. Extending longitudinally over the upper end of each tuyère chamber 14 are a pair of substantially parallel tubes 20 and 21. Tubes 20 and 21 are bent near the upper end of stoker 1, as shown at 22, so that the upper ends thereof lie in abutting relation with the inner surface of wall 7. The upper ends of tubes 21 and 22 may terminate in one of the steam drums of a boiler (not shown) or in a header which in turn may be connected to the boiler, as desired. The lower ends of tubes 20 and 21 are bent downwardly and forwardly, as shown at 23, and terminate in a header 24 disposed near the bottom of ash pocket A. The lowermost dead plate 25 of each retort 2 has mounted in cooling relation therewith one or more fluid conducting tubes 27. These tubes extend rearwardly from a header 28 mounted in any suitable manner beneath the stoker. The rearwardly disposed ends of tubes 27 are also bent downwardly and forwardly in substantially parallel relation with the tubes 20 and 21, and also terminate at the lower ends thereof in header 24. Headers 24 and 28 may also be connected to the boiler by downtake and riser connections 29 and 30 respectively. Tuyère supports 15 and 16, as shown more particularly in Fig. 2, are provided with rounded upper surfaces 31 and 32 respectively. Extending between rounded surfaces 31 and 32 and tubes 20 and 21 are side tuyère members 33 and 34. Each of the tuyère members 33 and 34 is similar in construction and accordingly a de-

tailed description of one will suffice for both. For the purpose of illustration, one of the tuyère members 33 will now be described in detail.

Each tuyère member 33 is comprised of spring steel construction and is provided with a substantially arcuate outer surface 35 and a pair of substantially arcuate inwardly extending legs 36 and 37. Outer surface 35 has extending lengthwise thereof a series of punched out tongues 38 which provide a series of openings through which draft air may pass to the fuel bed. As shown particularly in Figs. 1 and 3, the tongues 38 partially cover the openings, and thereby prevent siftings from passing into the tuyère chamber.

As pointed out before, tuyère members 33 and 34 are composed of spring steel, and the legs 36 and 37 thereof are so bent as to have a curvature corresponding with the upper surface of the tuyère supports and with the tubes 20 and 21. To assemble a tuyère member 33 or 34 in position, the legs thereof are inserted in the space between the tuyère supports and the tubes, and the member is then urged into position which, when assembled, corresponds to that shown in Fig. 2. The outer surfaces of the legs 36 and 37, it will now be observed, lie in intimate contact with the curved surface 31 and the tube respectively. To prevent movement out of position the tuyère members 33 and 34 may be spot-welded to the tubes 20 and 21.

Also extending between and lying in intimate contact with tubes 20 and 21 are a series of longitudinally extending intermediate tuyère members 39. Tuyère members 39 are somewhat on the order of tuyère members 33 and 34 and are also of spring steel construction. Tuyère members 39 are provided with a relatively flat upper surface 40 and a pair of downwardly extending legs 41 and 42. The upper surface 40 is provided with a hinged series of stamped out tongues 43 which provide a series of openings for draft air. The tongues 43, like the tongues 38 provided on tuyère members 33 and 34, partially cover the air openings, as shown more particularly in Fig. 4, and consequently the passage of siftings through said openings is reduced to a minimum. To assemble a tuyère member in position the legs 41 and 42 are forced between the tubes 20 and 21 so as to assume the position shown in Fig. 2. When in this position the outer sides of the legs 41 and 42 lie in intimate contact with the inner surfaces of said tubes. It will be noted that the upper surface of tuyère members 39 are disposed above the center line of the tubes 20 and 21, and consequently the weight of the fuel supported thereby will not move them out of operative position. To prevent the legs 41 and 42 from moving out of intimate relation with the tubes 20 and 21 due to expansion and contraction, the legs 41 and 42 may be welded to the said tubes. To prevent distortion of the tubes under load a series of tie members 44 are provided. These tie members are secured to the bolts 45 depending from and integral with said tubes 20 and 21. As shown in Fig. 2, the stud bolts 45 extend through apertures provided in tie member 44, and nuts 46 secure the parts in position. Tuyère supports 15 and 16 have also extending inwardly thereof apertured ears 47 and 48 respectively. These ears are secured to the depending portion 49 of tie members 44 in any suitable manner such as by bolts 50.

The side tuyère members 51 and 52 provided at the front or upper end of the stoker are of somewhat different construction from the side

tuyère members 33 and 34 disposed therebeneath. These members are provided with inwardly extending flanges 53 and 54 which seat upon inwardly extending flanges provided at the upper edges of side plates 12 and 13 respectively, and bolts 55 (Fig. 4) extending through said flanges secure the said tuyère members in position. The portions 56 and 57 of tuyère members 51 and 52 are slightly curved at the upper ends thereof, as shown at 58 (Fig. 1), and lie in abutting relation with tubes 20 and 21. The upper edges 59 of tuyère members 51 and 52 are flat and are provided with inwardly extending flanges 60 and 61, as shown more particularly in Fig. 6. A cover plate 62 having open tube receiving recesses 63 and 64, at the rearwardly disposed end thereof seats upon flanges 60 and 61, and stud bolts 65 extending through said plate, and tapped apertures in said flanges rigidly secure said cover plate in position. As shown in Figs. 1, 4 and 5, cover plate 62 extends across the top of the upper end of the tuyère chamber and around tubes 20 and 21, thereby preventing the passage of fuel siftings into the tuyère chambers. The upper intermediate tuyère member 66 is similar in construction to the intermediate tuyère members 39 except that the legs 67 thereof, which engage the inner surfaces of tubes 20 and 21, are shorter than the legs of tuyère members 39. The upper surface 68 of tuyère member 66 is curved, as shown in Fig. 4, to conform with the curvature of tubes 20 and 21, and is secured to the downwardly inclined tongue 69 of plate 62 by a stud bolt 70. The rearwardly disposed ends of the projections 71 and 72 of plate 62 abut the upper end of side tuyère members 51 and 52, as shown more particularly in Fig. 5.

By this construction it is seen that an effective seal is provided to prevent siftings from passing into the tuyère chamber. The lowermost side tuyère members 33 and 34, as well as the lowermost intermediate tuyère member 39, are so formed that the lower ends thereof will lie flush with lower dead plate 25 and the tuyère plate 73, as shown in Figs. 1 and 4. Draft air is supplied to the various tuyère members by means of a plenum chamber 74, which in turn may be supplied with air by any suitable fan or blower mechanism (not shown) through a communicating passage 75.

Figs. 7, 8 and 9 illustrate a modified tuyère construction consisting of a pair of tubes 76 and 77, having fins 78 and 79, welded or otherwise secured respectively to the outer sides thereof, and a series of intermediate tuyère members 80 disposed in intimate contact with the inner surfaces of said tubes. In this construction the side plates 81 and 82 defining the side walls of the tuyère chamber 83, have bolted, or otherwise secured thereto, series of tuyère supports 84 and 85 respectively. The upper ends of tuyère supports 84 and 85 have provided thereon a series of spaced projections 86 and 87, respectively, upon which the fins 78 and 79 rest. By this construction series of lateral air passages are provided between the fins 78 and 79, and the upper ends of tuyère supports 84 and 85.

Each intermediate tuyère member 80 is comprised of an upper, relatively flat portion 88, and a pair of curved legs 89 and 90. The rearwardly disposed end 88' of surface 88 extends beyond the legs 89 and 90, and in assembly overlaps the next lower tuyère member 80 of the series, and forms therewith, and the tubes at the sides thereof, passages 91 for draft air. To assemble

the intermediate tuyère members 80 in position the legs 89 and 90 thereof are forced between the tubes so as to occupy the position shown in Fig. 8. The legs may then be welded to the tubes so as to retain the said tuyère members in position.

Tubes 76 and 77 have also provided thereon depending stud bolts 92 and 93, the reduced lower ends of which extend through apertures provided in tie bars 94, and nuts 95 secure the parts in position. The outer ends of tie bars 94 extend into longitudinally extending recesses 96, 96 provided in tuyère supports 84 and 85. By this construction the tubes 76 and 77, and the tuyère members associated therewith, are effectively supported in position, the longitudinal recesses 96 permitting longitudinal expansion and contraction of the parts due to the variable temperature conditions to which the parts are exposed.

Figs. 10, 11 and 12 illustrate a further embodiment of the present invention. In this construction the upper end of each tuyère chamber 97 is bridged by longitudinally extending tubes 98 and 99 to which are respectively secured tuyère members 100 and 101. The sides of tuyère chamber 97 are defined by side plates 102 and 103, to the upper edges of which are bolted tuyère supports 104 and 105 respectively. Tuyère member 100 is provided with a substantially semi-circular recess 106 which receives the under surface of tube 98 and is secured thereto in any suitable manner, such as by spot-welding, as indicated at 107. The upper inner end of each tuyère member 100 is provided with a short, longitudinally extending flange 108 which is spaced slightly from a similar flange 109 extending inwardly from tuyère member 101. The outer side of tuyère member 100 is provided with a laterally extending portion 110 which terminates in a downwardly extending portion 111, which in turn abuts the outer sides of projections 112 extending outwardly from the upper end of tuyère supports 104.

Each tuyère member 101 is also provided with a semi-circular recess 113 which engages the under side of tube 99. Tuyère member 101 has also provided at the outer side thereof, a laterally extending portion 114 which terminates in a downwardly extending portion 115, which engages the outer sides of projections 116, extending laterally from the upper end of tuyère supports 105. It therefore is seen that the space between flanges 108 and 109 provide the necessary opening between the tubes through which draft air may enter into the furnace. The downwardly extending portions 111 and 115 also form with the upper ends of tuyère supports 104 and 105 downwardly extending passages through which draft air may also enter the furnace. Each tuyère member 101 is also secured to tube 99 by spot-welding, as indicated at 117. Tuyère members 100 and 101 have also provided at the bottom of the semi-circular surfaces thereof a recess 118 through which a stud bolt 119, depending from the tubes, may extend. These bolts also extend through apertures provided in tie bars 120, similar in construction to the tie bars 94 shown in Figs. 4 and 7, and which in turn are supported in suitable recesses provided in tuyère supports 104 and 105.

In all of the constructions just described, it will be observed that a relatively large area of the tuyère members are disposed in intimate contact with the fluid conducting tubes. The heat absorbed by the tuyère members therefore is readily conducted to the fluid circulating through said tubes, and as a result said tuyère members

are maintained relatively cool under all condition of operation. It will also be observed that the tuyère members are so constructed that a relatively large area is exposed to the incoming draft air, and consequently the cooling effect thereof is also imparted to the tuyère members.

As pointed out before, the tuyère members are constructed of resilient material, and when forced between the tubes snap into position and make intimate contact therewith.

It therefore is apparent that the various constructions comprising the present invention are not only simple in manufacture, and easy to install, but are capable of performance at maximum efficiency under the most severe conditions of furnace operation. By maintaining the various tuyère elements relatively cool, burnouts are reduced to a minimum, and consequently stokers may be operated without interruption for long periods of time.

While the embodiments herein shown and described are admirably adapted to fulfill the objects primarily stated, it is to be understood that the invention is not to be limited thereto, since it may be embodied in other forms, all coming within the scope of the claims which follow.

What is claimed is:

1. A tuyère construction for stoker furnaces comprising spaced, longitudinally extending members defining the side walls of a tuyère chamber, one or more fluid conducting tubes extending longitudinally over the top of said chamber, and tuyère members disposed between said tubes and said side members, said tuyère members being formed of relatively thin material, and a substantial portion of each of said tuyère members being of arcuate construction and conforming substantially to the curvature of said tubes, whereby in assembly said arcuate portions of said tuyère members lie in intimate contact with said tubes, and means for preventing lateral distortion of said tubes, said last mentioned means comprising a tie bar, and bolt means secured to and depending from each of said tubes for securing said tie bar in position.

2. A tuyère construction for stoker furnaces comprising two or more longitudinally disposed fluid conducting tubes, spaced supporting means for said tubes, tuyère members disposed between each of said supporting means and said tubes, a substantial portion of each of said tuyère members lying in intimate thermal contact with said tubes whereby said tuyère members are maintained relatively cool during operating periods of the furnace, additional tuyère members disposed between said tubes, substantial portions thereof lying in intimate contact with said tubes, and means for preventing lateral distortion of said tubes, said last mentioned means comprising a tie bar, and bolt means secured to and depending from each of said tubes for securing said tie bar in position.

3. A tuyère member adapted for assembly between a pair of fluid conducting tubes, said tuyère member being constructed of sheet metal material and being formed with a pair of downwardly extending legs of substantially arcuate construction and an upper fuel supporting portion, said legs being adapted to engage the inner surfaces of said tubes, and means for preventing lateral distortion of said tubes, said last mentioned means comprising a tie bar, and bolt means secured to and depending from each of said tubes for securing said tie bar in position.

4. A tuyère construction for stoker furnaces

comprising spaced, longitudinally extending members defining the side walls of a tuyère chamber, one or more fluid conducting tubes extending longitudinally over the top of said chamber, and tuyère members disposed between said tubes and said side members, each of said tuyère members being formed of resilient sheet metal and having a pair of legs of arcuate construction, and a fuel abutting portion bridging said legs, said tuyère members being so constructed that upon assembly thereof in position the arcuate portions of said legs lie in intimate contact with said tubes and supporting members.

5. A tuyère construction for stoker furnaces comprising spaced, longitudinally extending members defining the side walls of a tuyère chamber, one or more fluid conducting tubes extending longitudinally over the top of said chamber, and tuyère members disposed between said tubes and said side members, each of said tuyère members being formed of resilient sheet metal and having a pair of legs of arcuate construction, a fuel abutting portion bridging said legs, said tuyère members being so constructed 15 that upon assembly thereof in position the arcuate portions of said legs lie in intimate contact with said tubes and supporting members, and additional tuyère members disposed between said tubes, each of said additional tuyère members also comprising a fuel supporting portion, and a pair of depending legs of arcuate construction 20 which, in assembly, intimately engage the inner sides of said tubes.

6. A tuyère construction for stoker furnaces comprising spaced, longitudinally extending members defining the side walls of a tuyère chamber, one or more fluid conducting tubes extending longitudinally over the top of said chamber, and tuyère members disposed between said tubes and said side members, each of said tuyère members being formed of resilient sheet metal and having a pair of legs of arcuate construction, a fuel abutting portion bridging said legs, said tuyère members being so constructed that upon assembly thereof in position the arcuate portions of said legs lie in intimate contact with said tubes and supporting members, additional tuyère members disposed between said tubes, each of said additional tuyère members also comprising 35 a fuel supporting portion, and a pair of depending legs of arcuate construction which, in assembly, intimately engage the inner side of said tubes, and each of said tuyère members having a series of openings therein for draft air, 40 and tongues partially overlying said openings.

7. An inclined underfeed stoker, comprising alternately disposed retorts and tuyères, spaced side plates defining the side walls of said retorts and tuyère chambers, a pair of longitudinally extending tubes disposed above each of said chambers, a series of supporting members mounted on each of said side plates for supporting said tubes, a plurality of side tuyère members disposed between said tubes and said supporting members, a plurality of intermediate tuyère members disposed between said tubes, each of said tubes being curved upwardly at the upper end thereof, a pair of side tuyère members provided at the upper end of said stoker, a portion 55 of each of said side members being curved partially in conformity with the curvature of said tubes and having an upper, substantially horizontally disposed edge, a cover plate supported upon said horizontally disposed edges, an extension provided at the upper end of said stoker, a portion 60 of each of said side members being curved partially in conformity with the curvature of said tubes and having an upper, substantially horizontally disposed edge, a cover plate supported upon said horizontally disposed edges, an extension provided at the upper end of said stoker, a portion 65 of each of said side members being curved partially in conformity with the curvature of said tubes and having an upper, substantially horizontally disposed edge, a cover plate supported upon said horizontally disposed edges, an extension provided at the upper end of said stoker, a portion 70 of each of said side members being curved partially in conformity with the curvature of said tubes and having an upper, substantially horizontally disposed edge, a cover plate supported upon said horizontally disposed edges, an extension provided at the upper end of said stoker, a portion 75 of each of said side members being curved partially in conformity with the curvature of said tubes and having an upper, substantially horizontally disposed edge, a cover plate supported upon said horizontally disposed edges, an extension provided at the upper end of said stoker, a portion

tension provided on the upper of said intermediate tuyère members, said extension being curved in conformity with the curvature of said tubes, and means for securing the upper end of said extension to said cover plate.

8. An inclined underfeed stoker, comprising alternately disposed retorts and tuyères, spaced side plates defining the side walls of said retorts and tuyère chambers, a pair of longitudinally extending tubes disposed above each of said chambers, a series of supporting members mounted on each of said side plates for supporting said tubes, a plurality of side tuyère members disposed between said tubes and said supporting members, a plurality of intermediate tuyère members disposed between said tubes, each of said tubes being curved upwardly at the upper end thereof, a pair of side tuyère members provided at the upper end of said stoker, a portion of each of said side members being curved partially in conformity with the curvature of said tubes and having an upper, substantially horizontally disposed edge, a cover plate supported upon said horizontally disposed edges, an extension provided on the upper of said intermediate tuyère members, said extension being curved in conformity with the curvature of said tubes, means for securing the upper end of said extension to said cover plate, and each of said tuyère members comprising a fuel abutting portion, and a pair of substantially arcuate legs, adapted in assembly to lie in intimate contact with said tubes.

9. An inclined underfeed stoker, comprising alternately disposed retorts and tuyères, spaced side plates defining the side walls of said retorts and tuyère chambers, a pair of longitudinally extending tubes disposed above each of said chambers, a series of supporting members mounted on each of said side plates for supporting said tubes, a plurality of side tuyère members disposed between said tubes and said supporting members, a plurality of intermediate tuyère members disposed between said tubes, each of said tubes being curved upwardly at the upper end thereof, a pair of side tuyère members provided at the upper end of said stoker, a portion of each of said side members being curved partially in conformity with the curvature of said tubes and having an upper, substantially horizontally disposed edge, a cover plate supported upon said horizontally disposed edges, an extension provided on the upper of said intermediate tuyère members, said extension being curved in conformity with the curvature of said tubes, means for securing the upper end of said extension to said cover plate, and each of said tuyère members comprising a fuel abutting portion, and a pair of substantially arcuate legs, adapted in assembly to lie in intimate contact with said tubes.

10. An inclined underfeed stoker, comprising alternately disposed retorts and tuyères, spaced side plates defining the side walls of said retorts and tuyère chambers, a pair of longitudinally extending tubes disposed above each of said chambers, a series of supporting members mounted on each of said side plates for supporting said tubes, a plurality of side tuyère members disposed between said tubes and said supporting members, a plurality of intermediate tuyère members disposed between said tubes, each of said tubes being curved upwardly at the upper end thereof, a pair of side tuyère members provided at the upper end of said stoker, a portion

of each of said side members being curved partially in conformity with the curvature of said tubes and having an upper, substantially horizontally disposed edge, a cover plate supported upon said horizontally disposed edges, an extension provided on the upper of said intermediate tuyère members, said extension being curved in conformity with the curvature of said tubes, means for securing the upper end of said extension to said cover plate, each of said tuyère members being constructed of resilient sheet metal material and having a fuel abutting surface, and a pair of substantially arcuate legs adapted in assembly to snap into engagement with said tubes, and the said fuel abutting surfaces of each of said tuyère members having a series of openings therein for draft air, and means partially overlying said openings to prevent the passage of siftings into said tuyère chambers.

11. A stoker comprising alternately disposed retorts and tuyères, spaced side plates defining the side walls of said retorts and tuyère chambers, a pair of longitudinally extending tubes disposed above each of said chambers, a series of supporting members mounted on each of said side plates for supporting said tubes, spaced, upwardly extending projections provided on each of said supporting members, laterally extending fins provided at the outer sides of each of said tubes, said fins engaging said upwardly extending projections and defining therewith series of passages for draft air, and a series of tuyère members provided between said tubes, each of said tuyère members comprising an upper fuel

supporting surface and a pair of downwardly, substantially arcuate legs adapted in assembly to lie in intimate contact with the inner surfaces of said tubes.

5 12. A tuyère construction for stoker furnaces comprising a pair of longitudinally disposed fluid conducting tubes, spaced side walls forming a tuyère chamber, means mounted in intimate contact with said tubes and forming between said tubes openings for draft air, means extending outwardly from said tubes and disposed in operative relation with the upper ends of said side walls forming additional openings through which draft air may pass, and means for preventing lateral distortion of said tubes, said last mentioned means comprising a tie bar, and bolts secured to and depending from said tubes for securing said tie bar in position.

20 13. A tuyère construction for stoker furnaces comprising a pair of longitudinally disposed fluid conducting tubes, spaced side walls forming a tuyère chamber, means constructed of relatively thin material, mounted in intimate contact with said tubes and forming between said tubes openings for draft air, means extending outwardly from said tubes and disposed in operative relation with the upper ends of said side walls forming additional openings through which draft air may pass, and means for preventing lateral distortion of said tubes, said last mentioned means comprising a tie bar, and bolts secured to and depending from said tubes for securing said tie bar in position.
